CLAIM

The ornamental design for a container stand as shown and described.

DESCRIPTION

FIG. 1 is a front and right side perspective view of a container stand showing our new design; FIG. 2 is a rear and left side perspective view thereof; FIG. 3 is a front elevation view thereof; FIG. 4 is a rear elevation view thereof; FIG. 5 is a right side elevation view thereof; FIG. 6 is a left side elevation view thereof; FIG. 7 is a top plan view thereof; FIG. 8 is a bottom plan view thereof; and, FIG. 9 is a front and right side perspective view thereof, with a medical sharps container mounted therein.

The broken lines in FIG. 8 depict portions of the container stand that form no part of the claimed design. The broken

(Continued)

lines shown in FIG. 9 depict environmental subject matter and form no part of the claimed design.

1 Claim, 6 Drawing Sheets
